Frederick William Roffey, Montreal, Quebec, Canada, assignor to Melchers Distilleries, Limited, Berthierville, Quebec, Canada, a corporation of Quebec

Application April 16, 1934, Serial No. 51,418
In Canada March 15, 1934

Term of patent 14 years

To all whom it may concern:

Be it known that I, FREDERICK W. ROFFEY, a citizen of the Dominion of Canada, residing at Montreal, Province of Quebec, Canada, have invented a new, original, and ornamental Design for Bottles, of which the following is a specification, reference being had to the accompanying drawing, forming a part thereof, and in which:

Fig. 1 is a front view of a bottle showing my new design;

Fig. 2, a side view thereof;

Fig. 3, a rear view thereof; and

Fig. 4, a bottom plan view thereof.

I claim:

The ornamental design for a bottle as shown.

FREDERICK WILLIAM ROFFEY.
